COIN CONTROLLED ATTACHMENT

Joseph W. Srodulski, Chicago, Ill.

Application September 20, 1937, Serial No. 164,661

6 Claims. (Cl. 194—48)

This invention pertains to control devices for coin operated machines and more particularly to an improved control unit adapted for use as an attachment to various kinds of coin operated vending machines including dispensers of bottled beverages and the like.

A further object is the provision of a compact control unit including a mounting plate for ready attachment to a vending machine, slideable cover sections receivable on the mounting plate to enclose the mechanism, and operating mechanism including a manually operable control, dispensing mechanism and intermediate driving means between the operating lever and the dispensing mechanism, and including an automatic overload clutch to prevent forced operation of the device, and a coin operated latch mechanism to free the device for a single operation.

It is a further object to provide a coin controlled attachment having an operating lever controlled by coin-free means, means for directing a deposited coin into the coin-free means, indicating mechanism to show the number of operations of the device, and automatic means for blocking the coin directing means when the device has been operated a predetermined number of times.

It is a further object to provide dispenser actuating means having a normal or return spring arrangement and novel damping or braking means to relieve the strain when the mechanism is restored to normal.

A further object is the provision of improved overload clutch means for the prevention of forced operation of a device without deposit of a coin.

Yet another object is the provision of a rugged, compact structure including a housing therefor divisible into two sections slidably received in grooves formed on the attachment mounting plate.

Other objects and novel aspects both in the construction and operation of the attachment will become apparent as the following description proceeds in view of the several drawings in which:

Fig. 1 is a fragmentary vertical side section through the control mechanism and housing;

Fig. 2 is an enlarged front vertical section showing the control mechanism largely in elevation; the view being taken along line 2—2 of Fig. 1;

Fig. 3 is a fragmentary vertical side section taken along lines 3—3 of Fig. 2 through the coin control means;

Fig. 4 is a fragmentary horizontal section through the casing showing the automatic blocking means in plan, as seen along lines 4—4 of Fig. 2;

Fig. 5 is an elevational detail of the overload

clutch seen in the direction of lines 5—5 of Fig. 1;

Fig. 6 is an enlarged fragmentary vertical section of the coin latch mechanism as viewed along lines 6—6 of Fig. 3;

5 Fig. 7 shows the dispenser operating and brake means as viewed in rear elevation along lines 7—7 of Fig. 1;

Fig. 8 is an enlarged horizontal section through the dispensr operating mechanism as seen along 10 lines 8—8 of Fig. 7;

Fig. 9 is a perspective fragment of the casing flange means;

Fig. 10 is an enlarged sectional detail of the coin testing device as seen along line 10—10 in 15 Fig. 11; while

Fig. 11 is a horizontal sectional plan view of the coin testing device as seen along line 11—11 of Fig. 10.

The present control mechanism is adapted for 20 use with vending machines of all kinds and is particularly designed for cooperation with a coin control device of the general type shown in United States Patent 2,073,392, such device being in the nature of a cartridge or unit readily installed 25 in the control mechanism of this type and having coin operated latch releasing mechanism arranged for cooperation with the control mechanism to be hereinafter described.

The device of the present disclosure is preferably intended as an attachment and in one embodiment includes a substantially rectangular mounting plate 10 (Fig. 1) provided along its edge portions with a groove or channel formation 11 provided by narrow plate members 12 extended around the marginal portions of the mounting plate and spaced therefrom by spacers 13. This mounting plate is adapted for attachment to the wall of a dispensing cabinet or the like in which there is usually provided an opening 30 communicating with the dispensing mechanism.

The attachment is completed as a unit by the provision of a cover or housing in two separable sliding sections 14 and 15, having edgewise turned-in flange formations 16 on the top section 14, and shorter flange tabs 16' on the bottom section 15 (Figs. 2 and 9). Upper section 14 is positioned by sliding its flanges 16 in the grooves 11 and the bottom section is provided with an easy slip-on feature including laterally cut-out notched or slot portions 16'' in the base plate 10, dimensioned to receive the flange tabs 16' on the casing so that the latter may be directly or laterally worked or slipped into the grooves 11 instead of having to feed the leading edge of the flange into the beginning of the groove 11, as is done in the case of the upper section 14. The lower casing section 15 is provided with a suitable key lock means (not shown)

55 for preventing unauthorized removal, while the 60

upper section is screwed (not seen) into place since it is less frequently removed. Also, the top housing section 14 is provided with an entrance opening 17 (Fig. 3) into which coins are fed to actuate the latch releasing means.

The main control element is in the form of a manually operable handle 18 (Fig. 1) having an offset shaft portion 19 which extends through the housing and the mounting plate 10 for attachment at its inner end to the dispensing mechanism. Near its outer end this shaft 19 is provided with a collar 20 keyed thereto by means of a pin 21 and providing a bearing seated in a cross support 22 supported on spacer legs 23 (Fig. 6) attached to the mounting plate. At its inner end the collar 20 is keyed as at 24 to one member 25 of an overload release clutch to be described in detail hereafter. The companion member 26 of this clutch floats on the shaft 19 and has connected therewith a latch member 27 including a lateral pin 28 (Fig. 8) which extends through an arcuate slot 29 (Fig. 7) in the mounting plate for engagement with an operating arm 30 of the dispensing mechanism.

When the handle 18 is manipulated and the member 27 is not latched by the coin control means, the operating arm 30 is pivoted correspondingly and the same is provided with an angularly offset arm brake 31 and a smaller offset portion 32 from which extends a lateral pin 33 engageable in an arcuate slot 34 in a dispensing arm 35 which floats on the shaft 19. At one end the arm 35 is provided with a swivel connection 36 which is attached to a dispensing member or cord 37 adapted to pass over pulley means 38 for connection with certain dispensing mechanism, it being understood, however, that the dispensing arm 35 can be connected with any desired form of dispensing apparatus.

It will be apparent from Fig. 7 that when the principal operating arm 30 is rotated in an anti-clockwise direction the pin means 33 will engage the left-hand extremity of the slot 34 and pivot the arm 35 in the same direction to actuate the dispensing member 37. This movement is limited by the connecting stud or pin 28 in its arcuate slot 29 in the mounting plate 10.

The main operating arm 30 is urged in a clockwise direction into an initial or normal position by means of a strong spring 39 attached by stud means 40 and anchored by a stud 41 (Fig. 8) on the mounting plate 10. Should the handle 18 be released with the spring 39 under tension, the return movement of the dispensing member 37 is damped or relieved by means of a special cam brake including a member 42 pivoted between its ends as at 43 on the back of the mounting plate and having one end 44 enlarged to provide a weight constituting an inertia member, while at its other end there is a laterally extending cam roller 45 engageable with an edge portion 46 of the offset arm 31 of the main operating arm 30. The normal positions of the dispensing and braking mechanism are shown in full line in Fig. 7. But when the main operating handle 18 is freed by the coin testing device, the main operating arm 30 and the brake arm 31 move anticlockwise into the dotted line position with the dispensing arm 35 disposed in the dotted line position in the upper left quadrant, at which time the upper end portion of the dispensing arm adjacent the swivel connection 36 bears against the roller 45 on the cam brake member 42 and causes the latter to be moved somewhat in an anticlockwise direction as shown in dotted lines

in Fig. 7, this fact being pointed out to explain why the pendulum or weight is not in a perfectly upright position which it would otherwise occupy. If the patron of the machine restores

5 the operating handle 18 gradually to its normal position, the brake does not necessarily come into play. However, if the operating handle 18 is entirely released while the spring means 39 is tensioned the edge 46 of the cam brake 42 will 10 strike the roller 45 on the pendulum or inertia member and the latter will be rocked in a clockwise direction back into the full line position, the initial impact between the arm 31 and the roller 45, due to inertia of the member 42, immediately slowing up the return movement of the operating arm 30, and the camming action of 15 the roller working along the edge 46 thereafter limiting the rate of return movement of the dispensing mechanism to normal position.

20 The operating handle 18 and the intermediate clutch mechanism 28-27 are normally latched against movement by means of a latch dog 47 pivoted as at 48 on the front side of the mounting plate and having an offset nose 49 normally disposed in a segmental slot 50 provided in the periphery of the intermediate drive member 27 (Figs. 2, 3 and 6). The dog 47 is normally urged into latching position by means of a pin connection 51 with a coin controlled arm 52 having a horizontally disposed portion and a pair of upstanding portions adapted to deflect coins to either accept or reject the same dependent upon the test made by the mechanism comprising the testing cartridge or unit 53 (Figs. 3, 6 and 10) which arm 52 is mounted for pivotal movement within the unit 53 as at 170 and is freed for actuation by the deposit of a proper coin into the testing cartridge or unit 53 to raise the dog 47 out of latching position relative to the intermediate drive member 27 so that the latter can make a full stroke movement, there being normally an idle stroke movement equivalent to the length of the slot 50.

45 The foregoing idle stroke movement is utilized to effect operation of an arcuate arm 54 (Fig. 2) pivoted as at 55 on a bracket 56 secured to the mounting plate, this arm being normally urged in an upward or clockwise direction by means of a spring 57 connected to a lateral pin 58 extending therefrom near a reentrant nose 59 thereon, the upper end of this spring 57 being anchored to a tail 60 on a scavenger plate 61 pivoted as at 61' and having an offset inclined edge portion 63 directed toward the coin entrance 64 in the testing cartridge or unit 53 and cooperable with a stationary scavenger plate 65 to provide a short coin chute having its upper entrance end 66 disposed below the coin entrance 17.

50 In addition to normally closing the scavenger plate 61, the spring 57 urges the reentrant nose 59 of the arcuate arm 54 upwardly in its engagement in the slotted end of the vertically movable slide bar 67 of the testing cartridge or unit 53. There is a roller 68 on the intermediate clutch plate or member 27 which rides in the inner arcuate edge portion of the arm 54 and is effective when moved in a clockwise direction to depress the arm 54 and move the coin testing 55 unit slide bar 67 downwardly against the tension of spring 57, a distance adequate to initiate the coin testing operation; and if the coin is accepted, the latch operating pin 51 (see also Figs. 3 and 6) will be raised upwardly by the testing 60 cartridge or unit 53 so as to withdraw the latch

dog 47 from the segmental slot 50 (in a manner later to be explained), thus permitting full stroke movement of the intermediate clutch mechanism 26—27.

Each time the arcuate arm 54 moves downwardly, the movable scavenger plate 61 is pivoted into open (anti-clockwise) position by means of an angled arm 62 pivotally connected at its upper end to the scavenger plate as at 62' and having a slot connection at its lower end with the lateral pin 58 on arm 54. Thus, the scavenger is operated automatically upon each actuation of the intermediate drive and clutch mechanism 26—27.

The mechanism embodied in the coin testing cartridge or unit 53 is illustrated in Figs. 10, 11, and fragmentarily in Fig. 6. This cartridge or unit is well described and explained in the aforementioned patent to Knee, No. 2,073,392, dated March 9, 1937. Generally the cartridge 53 constitutes a housing having a suitable covering within which is positioned a frame to provide a coin passage at one side thereof (Fig. 10) adapted to receive coins deposited in the entrance 17. The slide bar 67 is formed as a part of this coin testing unit 53 and is arranged within the latter on the frame for vertically slidable movement and is normally urged upwardly by spring means 174 suitably anchored to the upper end of a yoke 153 which has its parallelly arranged leg members disposed in an annular groove formed in a collar member 154 slidably mounted for horizontal movement on a hub 140 formed as a part of the frame. When the slide bar 67 is urged downwardly in the manner above described by operation of the handle 18 and associated mechanism, a beveled portion 165 formed on the bar 67 bears against a beveled formation of a plate 190. This plate 190 is pivotally arranged on the frame and is disposed between the slide bar 67 and the legs of the yoke 158 such that the descending movement of the beveled portion 165 will urge the plate 190 to the right. An arm 189 has one end portion thereof formed to provide a tongue and adjacent shoulders, which tongue is disposed in a slot formed in the plate 190 whereby the arm 189 is loosely carried by the plate 190, there being a spring associated with the arm 189 to urge the latter in a general direction toward the plate 190. The arm 189 and the plate 190, through the spring and tongue connection therewith, are urged in a clockwise direction by a spring member 194 and the free end of the arm 189 has a slot formation which is normally adapted to engage a cross bar 188 extending between a pair of laterally disposed legs formed as a part of a presser member 260 disposed adjacent the aforesaid coin passage and having its lower end pivotally arranged on the frame as at 170. The rocking movement of the plate 190 and the arm 189 draws the presser member 260 in a clockwise direction about its pivot mounting against the action of a resilient tongue formed as a part of one wall of the coin passage and having its free end bearing against the upper end of the presser member 260. Assuming that a coin has previously been inserted and stopped at the point A by horizontally sliding pins (not shown), a presser pin 270 carried by the member 260 in axial alignment with the hub 140, will be urged against the deposited coin so as to urge the latter against the end portions of feeler members 149. These feeler members are arranged to rock on an annular ring 159 mounted coaxially with respect to the hub structure 140, with the elongated oppositely dis-

posed free ends of the feelers 149 disposed normally to abut a shoulder formation on the sliding collar 154 by action of a spring element 151 surrounding the feeler members 149 in their assembled relation.

The arrangement is such that the short ends (left ends) of the feelers 149 are adapted to engage the face of the deposited coin to make a facial reading thereof. If there are no configurations on the right-hand surface of the coin, the feelers will pivot uniformly upon the annular ring 159 so that the elongated end portions of the feelers will swing away from the hub structure and beyond the shoulder formation on the collar 154, freeing the latter and the yoke 158 linked thereto for movement to the left.

The coin controlled arm 52 likewise mounted on the pivot 170, has a pair of upstanding portions 181 disposed in the coin passage below the testing point A so as to deflect coins toward a reject or acceptance opening determined upon the test made by the feeler members. This arm 52 is normally urged counterclockwise (Fig. 10) by spring means 206 extending between a horizontal portion of the arm 52 and the lower end portion of the yoke 158. The arm 52 and deflector portions thereof 181 are normally held in the position shown by a toggle arrangement 208 which is broken only when the slide bar 67 reaches its maximum lowered position. Therefore, the arm 52 and deflector portions 181 are held in coin returning condition until the entire testing operation has been performed.

A strut 198 is pivotally arranged at its upper end as at 199 on the frame of the unit 53 and has its lower end adapted to block normal movement of the arm 52 when the toggle 208 is broken. The strut 198 is employed to gauge the thickness of the coin being tested, and this is accomplished by a pin 197 carried by the arm 189 and movable therewith when the presser member 260 is swung as aforesaid. Thus, the pin 197 causes the strut 198 to swing at 199, and if the coin is of a proper thickness the end of the strut 198 will stop at a point adjacent the arm 52 where an opening 179 is formed in the arm 52 so as not to abut the latter but permit movement thereof when the toggle 208 is broken.

The feelers 149 having by facial reading of the coin assumed the aforesaid position beyond engagement with the sliding collar 154, the slide bar 67 continuing in its downward movement until an oblique extension 166, formed as a part of slide 167, bears down upon the arm 189 to pivot the latter and the plate 190 against the action of the spring 194, thus moving the free end of the arm 189 to disengage the cross bar 188 whereby the latter and the arms 186, pin 197, and presser member 260 are free to swing back to their normal position by the resilient tongue aforesaid. Simultaneously with the foregoing movement of the presser member 260, the slide bar 67 will have engaged the upper link of the toggle 208 to break the latter and free the arm 52 for pivotal movement just prior to the release of the coin from pressing engagement by the pin 270.

If, as before stated, the facial reading was such as to swing the feelers 149 out of engagement with the sliding collar 154, the yoke 158 by action of the spring 206 will pivot on its legs so that the lower end of the yoke will abut the right portion of the arm 52 and no movement of the latter will result. In that event, the coin will be returned to the depositor. However, if the configurations on the coin were of a proper contour, the facial read-

ing effected by the feeler members 149 is such that the elongated end portions of the feelers 149 will abut the shoulder formation on the sliding collar 154, thus preventing pivotal movement of the yoke member 158 and permitting counter-clockwise movement of the arm 52, together with the deflector portions 181, to collect the coin. This pivotal movement of the arm 52 causes the pin 51 by its connection therewith to move upwardly (Fig. 6), thereby swinging the dog 47 counterclockwise about its pivot 48 to disengage the offset nose 49 of the dog from latching engagement with respect to the intermediate clutch member 27, thus freeing the latter for normal dispensing operation.

Should the slide bar 67 be restrained upon idle stroke operation of the clutch means, the arcuate arm 54 is arranged to yield by the provision of a slot 135 at its opposite end and embracing the pivot 55, spring means 93' suitably anchored to the plate 10 and normally holding the arm 54 up against the pivot 55 to fulcrum on the latter when the opposite end is free to move.

In order to prevent retrograde movement of the intermediate clutch mechanism 26—27 when its full stroke movement has begun, there is provided a full stroke dog 70 (Fig. 2) pivoted as at 71 to the mounting plate and normally positioned as seen in Fig. 2 by a spring 72 anchored on the mounting plate 10, and with its nose disposed in a small segmental notch 73 in the intermediate clutch member 27. There are provided a plurality of notches 74 between the segmental notches 50 and 73 and in which the nose of the dog 70 rides to prevent reverse movement of the clutch member 27 until the notch 50 is turned (clockwise) so as to permit the dog 70 to project its nose therein, whereupon the dog will be pivoted in a clockwise direction upon the return (anti-clockwise) movement of the clutch member 27.

In order to prevent the loss of the deposited coin by failure of the operator to continue the operating movement of lever 18, there is provided a safety latch 75 (Fig. 2) also pivoted at 71 and having a lateral nose 76 automatically positionable by gravity in front of an offset nose portion 77 on the the latch dog 47 to block return of the nose 49 of the latch dog 47 into the notch 50 until the member 27 has made a complete operative movement. This safety latch 75 is automatically pivoted out of blocking position by means of a tail 78 on the dog 70 and which is engageable with an offset ear 79 on the safety latch 75 such that when the full stroke dog 70 pivots in a clockwise direction responsive to the return movement of the clutch member 27, the safety latch 75 will likewise be pivoted in a clockwise direction to raise the lateral nose 76 thereof out of the path of the latch dog 47, this being effected through engagement of the tail 78 on the full stroke dog with the offset ear 79 on the safety latch.

Indicating mechanism is provided in the form of a ratchet wheel 80 (Figs. 1, 2 and 4) having a number of teeth corresponding generally to the quantity or number of articles of merchandise with which the machine can be loaded at one time, provided on its outer surface with indicia characters 81 corresponding in this instance to every five teeth. This ratchet wheel 80 is rotatably mounted on a shaft 82 extended from the mounting plate and is provided with a spring 83 anchored on a stud 84 normally urging the ratchet in an anti-clockwise direction into normal or initial position. Step by step advancing

movement of this ratchet is effected through a gravity-positioned dog 85 pivoted as at 86 on an elongated ratchet drive arm 87 also pivoted on the stud 82.

- 5 The ratchet arm 87 has a lower manually engageable end 88 which protrudes below the bottom margin of the top half of the housing section, such that when the lower half is removed, the attendant may manipulate the lever 87 to reset the device. Each full stroke (clockwise) movement of the intermediate drive member 21 effects a reciprocation of the ratchet arm 87 by means of a lateral roller 89 on the intermediate member 21 which engages with the lower left-hand edge portion 90 of the lever 87 and pivots the latter against the tension of a return spring 91 in an anti-clockwise direction, thus moving the ratchet dog 85 a distance of one tooth so that when the spring 91 restores arm 87, the ratchet wheel 80 will move a distance to indicate the dispensation of one article. Retrograde movement of the ratchet wheel is prevented by means of a dog 92 normally positioned by means of a spring 93 to project an edge portion 94 against the teeth.
- 10 15 In order to restore the ratchet wheel 80 to normal position, it is merely necessary to engage the lower end 88 of the ratchet arm 87 and pivot the latter in an anti-clockwise direction so as to dispose the hooked end 85' of the ratchet dog 85 against the offset end 95 of the stopping dog 92 so as to pivot the latter out of engagement with the teeth of the disc whereupon the clock spring 83 will restore the ratchet wheel to initial position.
- 20 25 30 35 40 The upper housing section 14 is provided with a sight opening 96 (Fig. 1) and a sighting sleeve 97 having a lens 98 at its inner end in position to read the indicia 81 on the ratchet disc so that the attendant may know the condition of the stock in the machine.
- 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
- 4 Movement of the ratchet arm 87 toward the

right (Fig. 2) to release the stopping dog 92 will cause the upper end 130 of the ratchet arm 87 to bear against a depending lug 131 on the blocking plate 100, thus shifting the latter (left) into opening position wherein it will be locked by the substantially simultaneous release of the release arm 106.

It may be observed here that the release plate 106 is provided with pin means 132 extending from the base plate into a slot 133 in the plate 106 such that the latter can drop only a short distance when released.

Means is provided in the form of an overload clutch of especial design for preventing forced operation of the mechanism to avoid deposit of a coin. This overload clutch, as seen in Figs. 1 and 5 particularly, includes a front disc member 25 rotatable with the shaft portion 19 of the operating lever 18 while the companion plate or disc 26 floats on the shaft 19, but is normally keyed to the member 25 by means of an ear 115 having cammed edge portions 116 receivable in a segmental slot 117 in the keyed member 25. The extension 115 is provided on the inner arcuate edge portion of a yoke arm 118 pivotally mounted as at 119 on a portion of the float disc 26 and normally urged in an anti-clockwise direction (Fig. 5) by means of a spring 120 anchored at one end to an ear 121 on the floating member 26 and at its other end to an ear 122 at the other end of the yoke arm 118, movement of the latter being limited by means of a pin 123 on the float arm 26 and extending through an arcuate slot 124 in the yoke arm.

Briefly, the operation of the device is as follows: The operator of the machine facing the control unit with the parts disposed as in Fig. 2, deposits a coin in the entrance 17, such coin passing through the scavenger device 63—65 into the coin testing mechanism of the cartridge 53 where the coin is held until the testing device is actuated by turning the operating handle 13 which turns the shaft 19 in a clockwise direction, thus causing the roller 68 on the intermediate operating disc to bear down on the actuating arm 54 and pivot the latter about the point 55 so as to draw the vertically movable slide bar 67 down into the dotted line position. If the coin be a proper one, the latch dog 47 will be pivoted in a clockwise direction into ineffective position out of the notch 50 in the intermediate operating disc, whereupon the latter is freed for completion of its clockwise rotative movement by the operator with the result that the pin 28 will pivot the dispensing arm 30 (in an anti-clockwise direction as seen in Fig. 7), which in turn moves a dispenser arm 35 in a similar direction into the dotted line position shown in the latter figure and which position corresponds to the movement of the operating handle to its limit. Should the operator release the handle in this position for any reason, the spring 39 will tend quickly to return the dispensing lever 30 to its full line position; however, such return movement will be limited by the brake pendulum 42—45, as heretofore described.

Meanwhile, the intermediate operating disc 27 (Fig. 2) will have been turned to its limit in a clockwise direction so as to cause the roller 89 to bear against the ratchet operating lever 87 and pivot the latter in an anticlockwise direction to step the counting disc 80 a distance equivalent to the counting of one article of merchandise.

In case the handle 18 is manipulated without deposit of a coin, the intermediate operating disc 27 has a limited idle stroke freedom of movement corresponding to the arc of the slot 50, and this movement is sufficient to cause the roller 68 to bear down on the actuating arm 54, the latter pivoting on its compound pivotal mounting 55—135 while the opposite end of the arm which is attached to the coin tester shifts downwardly and operates the coin tester without, however, freeing the disc 27 for full movement, and when the intermediate disc 27 is restored to normal the spring 57 will shift the arm 54 and its pivot 58 up to normal position in the slot at the bottom of arm 62.

When the counting disc 80 has made a predetermined number of steps constituting substantially one revolution, the pin 112 on the back of the disc will engage the release arm 106 to move the latter upwardly and unlatch the coin blocking plate 100, so that the latter will be moved by its springs to block the coin opening 17.

The counting disc 80 may be restored to normal by the attendant, who will grasp the handle portion 88 of the lever 87 and pivot the latter in an anticlockwise direction until the offset nose 85' of the ratchet dog 85 bears against the offset ear 95 of the dog 92 to pivot the latter out of engagement with the teeth of the disc so that the now tensioned spring means of the ratchet disc will rapidly turn the latter back to its normal position. At the same time, the upper end 130 of the lever 87 will bear against the lug 131 on the coin blocking plate 100 and shift the latter back into ineffective position, the latch plate 106, meanwhile, being raised by the restored ratchet plate pin 112 into latching position, so that the blocking plate is held open.

In summary, the invention herein provides for an improved coin control unit preferably in the form of an attachment adapted for mounting on any vending machine, the unit housing being of a novel construction comprising two separable casting sections slidable on a base plate and further providing a coin deposit and a sight opening, and operating mechanism including a handle connected through an overload clutch with intermediate driving means normally latched by coin operated means adapted to receive coins, step by step indicating mechanism arranged for viewing through the sight opening, automatic blocking means to prevent further deposit of coins when the supply of merchandise is exhausted, together with dispensing mechanism and novel braking means therefor, all arranged to provide a compact, rugged and fool-proof attachment, the form and arrangement of the several parts of which are subject to modification, all of which modifications and equivalent arrangements are intended to be included within the call of the appended claims.

Having thus described my invention, what I claim as new and desire to protect by Letters Patent is:

1. In dispensing machines, operating mechanism including a driven shaft, a dispenser arm floating on said shaft and having a radial cam edge, spring means normally urging said arm into an initial position, means on said arm operatively connected with dispensing mechanism and adapted to move with said arm to effect operation of said dispensing mechanism, and brake means including a brake arm pivotally mounted between its ends eccentrically of said shaft near said dispenser arm and having lateral pin means

engageable with said radial cam edge, said brake arm being provided with means normally disposing the same to position said lateral pin means thereon near the radial extremity of said cam edge, together with means on said shaft and connecting the latter with said dispensing arm for turning said dispenser arm against the tension of said spring means.

2. In combination, a movable operating element, releasable latch means normally preventing effective movement of said operating element but permitting limited idle stroke movement thereof, coin testing means operable to release said latch means upon deposit of a proper coin therein, a counting device arranged to count the effective operations of said operating element, means actuated by said operating element when the same moves in idle stroke movement to operate said testing means, and means actuated by said operating element when the same is moved responsive to release of said latch means for operating said counting device.

3. In combination, a coin testing device including a reciprocal actuating member, releasable latch means released by said testing means responsive to operation of said actuating member when a proper coin is deposited in the testing device, a control member mounted for rotative movement, said latch means being arranged normally to limit the movement of said control member and releasable to permit free movement thereof, pivot means and means including an arcuate lever arm operatively connected near one end with said actuating member of the testing device and having slotted engagement with said pivot means near its opposite end so as to be shiftable laterally of said pivot means as well as pivotable relative thereto, spring means engageable with said opposite end of the lever arm and urging the latter into one of its shiftable limits for pivotal movement relative to said pivot means, means carried by said control member and extending therefrom and adapted to move rotatively therewith in a plane substantially parallel to that in which said arcuate lever arm moves and being arranged on said control member with respect to said arcuate lever arm to engage the latter between its ends to pivot said arm about said pivot means by limited movement of the control member as aforesaid in a particular direction, whereby to move said actuating member to effect release of said latch means and permit continued movement of the control member in said direction, said lever arm shifting relative to said pivot means to permit such continued movement of the control member.

4. In combination, a coin testing device having an actuating member, a control member arranged for rotative movement, latch means normally limiting the rotative movement of the control member and releasable by said coin testing device to permit free movement of the control member, and an arcuate lever arm operatively connected near one end with said actuating member and having support at its opposite end for both pivotal and translating movement, yieldable means normally restraining the translating movement of said arm, roller means carried by said control member for movement therewith and disposed to move in a path traversed by said arcuate lever arm, said arm being engaged between its

ends by said roller means and pivoted thereby to move said actuating member when said control member is limitedly moved, said lever arm pivoting in the region of said actuating member of the testing device and translating in the region of its end opposite thereto when said control member is freely moved upon release of said latch means, together with yieldable means normally urging the end portion of the lever arm connected with the actuating member in a direction opposite to its direction of movement by said control member.

5. In a device of the class described, means for operating a coin testing device including a reciprocal actuating member said means including a control member arranged for rotative movement, an arcuate arm disposed in a plane substantially parallel to the plane of movement of said control member, means pivotally mounting said arcuate arm near one of its ends, an elongated slot formed at one end of said arcuate arm and cooperating with said pivotal mounting to render the arcuate arm shiftable relative to said pivotal mounting means, said arcuate arm having its opposite end operatively connected with said actuating member, spring means connected with each of said ends of the arcuate arm and urging the same in a direction toward said pivotal mounting means and in a direction to move said actuating member toward one of its reciprocal limits respectively, cam means on said control member and extending into the plane of movement of said arcuate arm, said control member and said cam means being movable in a particular direction with the latter adapted to bear against said arcuate arm between its ends to effect movement of said actuating member upon movement of the control member a predetermined distance in said particular direction, said arcuate arm subsequently shifting relative to said pivotal mounting means upon continued movement of the control member in said particular direction.

6. In a device of the class described including a coin testing unit having a reciprocal actuating member, means for operating said reciprocal actuating member, said means including an arcuate arm having pivotal support at its opposite ends and being arranged to shift relative to said pivotal support at both ends, spring means engaging said opposite ends of the arcuate arm to shift the same in a particular direction to the limit of their shifting movement, means at one of said ends of the arcuate arm operatively engaging said actuating member, a control member arranged for rotative movement a predetermined amount in one direction, means on said control member and arranged to move in a path traversed by the mid section of said arcuate arm and adapted to engage said arcuate arm between its ends and pivot the same about its end opposite the connection with said actuating member to effect shifting movement at said last-mentioned end and urge the actuating member in a direction opposite to said aforementioned particular direction, said arm subsequently shifting at its end opposite the actuating member upon continued movement of the control member in said direction.

JOSEPH W. SRODULSKI.
